UNITED STATES PATENT OFFICE.

BAYLUS E. EARLE, OF DANVILLE, ILLINOIS.

MIXER.

Application filed December 16, 1926. Serial No. 155,140.

My present invention, in its broad aspect, has reference to improvements in means and methods of properly mixing bitumastic or asphaltic products with suitable fillers, as for instance clay dust; standard specifications for asphalt road construction material usually calling for approximately sixty percent filler. The filler must be uniformly and thoroughly mixed with the asphalt, and the operation must be carried out economically and quickly in commercial practice, and to obtain a proper mix between the filler and the asphalt it is desirable that the mixing operation be carried out while the asphalt is kept at the boiling point or at a relatively high temperature. More particularly it is my purpose to evenly distribute the filler (clay dust or the like) over the surface of the asphalt in the kettle, to heat the asphalt and keep it at or above the boiling point, and to agitate the contents of the kettle thoroughly and uniformly by air and steam. Other devices with which I am acquainted and some of which purport to accomplish a similar end do not provide, among other things, means for preventing clogging of the vent of the pneumatic agitators, nor can the filler material be uniformly and properly distributed over the surface of the asphalt body. I prevent clogging of my apparatus by utilizing a combination of live steam and air, or either steam alternately with air to agitate the asphaltic mix thereby eliminating clogging of the vents of my agitating mechanism, and attaining a more homogeneous mass. Uniform distribution of the filler is attained in my apparatus by progressively discharging the same over a large portion (or the whole) surface of the asphalt in the kettle at a point slightly above the surface thereof; adjustable means being provided to regulate the height of the filler discharge means from the surface of the asphalt which gradually rises as the boil is produced and the mix carried out. It is also one of the advantages of my invention that all parts are readily accessible, replaceable, and easily set up and operated with a consequent saving in labor and material. Other and equally important objects and advantages will become apparent as the description of my apparatus proceeds, but while I have in the present instance defined for the sake of illustration an apparatus of a certain specific form, it will be understood

that I do not desire thereby to limit myself except as may be indicated by the scope of the claims appended hereunto and forming a part of this specification.

In the drawings wherein is illustrated an embodiment of my invention;

Figure 1 is a side elevation of my apparatus, partly diagrammatic, and partly broken away, to show certain details thereof,

Figure 2 is an end view thereof partly broken away,

Figure 3 is a detail view of the heating and agitating elements of my apparatus, and

Figure 4 is a detail view of the universal connection which I employ to enable me to swing my filler discharge pipe over the surface of the asphalt in the kettle.

In the drawings wherein like characters of reference are used to designate like or similar parts throughout the several views;

The numeral (1) designates a screw or other type of conveyor for transporting the filler (clay dust or the like) from a suspension machine such as described in my co-pending application filed December 16th, 1926, Serial Number 155,141. The conveyor (1) is mounted in a housing (2) supported on a raised platform (3) having discharge openings (4) therein as shown by dotted lines in Figure 1. The openings (4) are provided with slide valve elements (5) operated manually by a rod (6) and lever (7) pivotally suspended from a suitable base as at (8). Below each discharge opening and suspended from the platform (3) as by brackets (9) is a hopper (10) leading to a bell-shaped or semi-spherical hollow member (11). Each member (11) is provided with a pin (12), and extends through an opening (13) to pivotal engagement in the head (14) of a vertically arranged down pipe (15). By the aforementioned means each pipe (15) is swingably hung from its member (11), each of which in turn is suspended from the platform (3) beneath a discharge opening (4). Adjustably carried upon each of the pipes (15) is a strap (16) to which is pivoted a pitman (17) connected with a crank shaft (18) journalled in bearing elements (19) on supports (20). The crank shaft is power driven by means, not shown, to swing the pipes (15) back and forth, the strokes being regulated as to length by the positions of the straps (16) thereon.

Upon the lower end of each pipe (15) is a cuff, or loose extension (21) which is adjustable in position on the pipe by a chain (22). Below each of the pipes (15) is an asphalt kettle (23), and around each kettle is a platform (34). The kettles are supported on suitable bases (24) preferably of brick or like construction. The pipes (15) swing over the surface of the asphalt in the kettles to discharge the filler material (clay dust or the like) from the conveyor (1), and the strokes of the pipes are regulated to cover as much of the surfaces as possible, which in some cases is the whole exposed surface of the asphalt; the cuffs or extensions (21) being adjusted to be slightly spaced from the surface of the asphalt.

Asphalt is loaded into the kettles through service pipes (25) and the mix of asphalt and filler is discharged or unloaded through connections (26). In order to properly mix the filler with the asphalt it is desirable that the same be maintained at a boiling or high temperature, and to this end I provide a plurality of pipe coil banks (27), each bank being spaced from the others by a plate (28), and the whole covered by a plate (29). These coils are connected with a live steam line (30); a suitable valve (31) being provided to regulate the delivery of steam thereto.

In order to agitate the bodies of asphalt in the respective kettles to properly mix the filler therewith, I employ both compressed air and live steam, same being delivered through service pipes (32) and (33), from which down pipes (35) connect with spaced vent pipes (36) on the bottoms of the kettles, below the coils. From each down pipe (35) is a by-pass (37) to air line (33) so that either air or steam, or both air and steam may be delivered to the vent pipes (36) by adjustment of valves (38), and the quantity of each also regulated. The vent pipes (36) have a plurality of openings (39) directed down, or toward the bottoms of the kettles, and the vent pipes are spaced from the heating coils by angle irons (40). A suitable drain line (41) is provided for the heating coils in which is interpolated a valve (42) for opening and closing the same.

The operation of my apparatus is as follows; asphaltic material is projected into the kettles (23) through connections (25) from a storage tank (not shown). The kettles having been filled to the desired level say to the dot-and-dash lines in Figures 1 and 2, steam is directed into the coils (27), through pipe (30) by opening valve (31) and the asphalt raised to a boiling temperature or to a very high temperature above the boiling temperature. It is kept at this temperature while the operation is completed. Filler material (clay dust or the like) is delivered to the pipes (15) from con-

veyor (1), valves (5) being open. The shaft (19) is actuated to swing the pipes (15) back and forth over the surface of the asphalt in the kettles to uniformly spread or distribute the same. The asphalt level raises with the temperature and with the incorporation of filler material therein, and cuffs or extensions (21) are adjusted by chains (22) to maintain a uniform spaced relationship between the discharge end of the pipes and the level of the asphalt. As the filler is fed into the kettles, the asphalt is agitated by causing exhaust of air, or air and steam, or steam through the vents (39) in pipes (36), same being regulated by valves (38). It has been found that ordinary pneumatic agitating apparatus becomes clogged and inoperative because of asphalt passing into and congealing within the vent openings of the vent pipes. By the use of live steam or air and steam, the openings are kept open and clear by reason of the action of the steam, and this action is facilitated by forming the vent openings in the bottoms of the pipes, facing the bottoms of the kettles, instead of in the tops of the pipes. When a sufficient quantity of filler has been mixed with the asphalt, the kettles are emptied through connections (26) and the operation repeated.

While in the foregoing, there has been illustrated in the drawings and described in the specification such combination and arrangements of elements as constitute the preferred embodiments of my invention, it is nevertheless desired to emphasize the fact that interpretation of the invention should only be conclusive when made in the light of the subjoined claims.

I claim;

1. Apparatus for mixing asphalt with filler comprising a receptacle for holding the mixture, means for discharging air and steam into the receptacle for agitating the contents thereof, and independent means for separately regulating the relative amounts of air and steam.

2. Apparatus for mixing asphalt with filler comprising a receptacle for holding the mixture, means for discharging air and steam into the receptacle and toward the bottom of the receptacle for agitating the contents, and means for regulating the amount of air and steam.

3. Apparatus for mixing asphalt with filler comprising a receptacle for holding the mixture, swingable means for distributing the filler upon the asphalt, means for regulating the stroke of said swingable means, means for regulating the space between each of said means and the surface of the asphalt, and means for introducing fluid under pressure into the mass to agitate the same.

4. Apparatus for mixing asphalt with filler comprising a receptacle for holding the

- mixture, means for heating the mixture, swingable means for distributing the filler upon the surface of the asphalt, means for regulating the stroke of said swingable means, means for introducing steam and air into said receptacle to agitate the contents thereof, and means for regulating the amount of steam and air delivered into said receptacle.
- 10 5. Apparatus for mixing asphalt with filler comprising a conveyor for the filler, a receptacle for holding the mixture, means for heating the mixture, swingable means for directing the filler from the conveyor upon the surface of the asphalt, means for regulating the discharge from the conveyor to said swingable means, means for regulating the stroke of the swingable means, means for introducing steam and air into the receptacle and directing the same toward the bottom of the receptacle to agitate the contents thereof, and means for regulating the amount of steam and air delivered into said receptacle.

In testimony whereof, I affix my signature 25
hereunto.

BAYLUS E. EARLE.
